UNITED STATES PATENT OFFICE.

BIRGER LJUNGSTRÖM, OF STOCKHOLM, SWEDEN.

ELASTIC-FLUID TURBINE.

No. 919,196.

Specification of Letters Patent.

Patented April 20, 1909.

Application filed March 27, 1908. Serial No. 423,684.

To all whom it may concern:

Be it known that I, BIRGER LJUNGSTRÖM, of 18 Grefmagnigatan, Stockholm, Sweden, civil engineer, have invented certain new and useful Improvements in Elastic-Fluid Turbines, Compressors, and Such Like; and I do hereby declare the following to be a full, clear, and exact description of the invention, such as will enable others skilled in the art to which it appertains, to make and use the same, reference being had to the accompanying drawings, and to letters or figures of reference marked thereon, which form a part of this specification.

This invention relates to improvements in elastic fluid turbines which are operated by the gradual expansion of the driving medium between relatively movable vane rings arranged in concentric groups. These vane rings may be mounted on the opposing faces of two oppositely rotatable vane disks mounted on separate shafts or arranged with one or more vane systems stationary and the others rotary. In the latter case a rotating system is usually arranged on each side of a rotating disk and the stationary systems on both faces of the casing.

In a double rotary vane ring the axial pressure of the driving medium is balanced, in that the medium has access to both sets of vanes, while in a single rotary vane system one of the sets of vanes is replaced by baffling devices, placed between the rotary disk and the stationary part of the turbine casing.

The economy of the turbine depends, to a great extent, on the amount of leakage of the driving medium past the outer edges of the vane rings, and the amount of leakage depends upon the distance between the rotary and the stationary parts during the working of the turbine. This distance, however, must, under all circumstances, be sufficiently great to prevent contact of the parts due to varying pressure or contraction or expansion due to the varying temperature.

The object of the invention is to provide means for adjusting the various parts of the turbine to compensate for the changes in form due to the causes named.

In the accompanying drawings:—Figure 1 is a vertical section of a radial turbine embodying the features of my invention. Fig. 2 is a vertical section of an adjusting mechanism. Figs. 3 to 6 are vertical sections of modified forms of turbines having my invention applied thereto.

In Fig. 1 of the drawings two disks as 1, are shown each of which is fastened to a separate shaft 1^a and carrying a plurality of vanes 2 mounted in concentric rows and arranged to rotate the disks in opposite directions. The axial pressure of the driving medium between the disks is, as usual, balanced by the driving medium leaking through baffling plates 3 which driving medium is supplied to the vanes and baffling plates through an inlet 4 and channels 5 and escapes through an outlet 6 in the housing 7.

One set of baffling plates 3 are as usual mounted on the outer faces of the disks but instead of mounting the co-operating baffle plates on the inner walls of the turbine housing, in the usual manner, I provide non-rotatable adjustable pressure plates 8 and 12 inside the turbine housing 7 between said inner walls and the outer faces of the disks. Said plates are mounted in the side walls of the housing forming journals for the shafts and as they project beyond the peripheries of the disks are connected together by means of stay-bolts 9 so that all axial pressure is taken up by the plates. Stuffing boxes as 10 are provided around shafts and that portion of the pressure plates 8 and 12 which project into the housing and form a fluid tight connection between these parts.

By the provision of the pressure plates the warmer driving medium may be conducted to the vanes of the turbine through channels in one or both of the plates without the resulting expansion of the plates being communicated to the housing. This is of great importance, especially in radial turbines having a central inlet for the driving medium, where differences in tension between the warm inlet and cooler outlet cannot, as in axial turbines, be counterbalanced along a long interlying turbine drum.

The inlet 4 for the starting and the inlet 11 for the overcharging may, as shown, be formed in the pressure plates 8 and 12 respectively. The overcharging inlet communicates by means of channels 13, in the pressure plate 12 and channels 14 in the disks, with vane interspace 15 and the starting inlet 4 also communicates with said interspace through channels 14. Outlets 16 and 17 may likewise be arranged in the pressure plates for the driving medium which leaks through the shaft journals. These inlets and outlets are connected with ports in the turbine housing by slidable or resilient con-

nections to provide for the expansion and contraction of the pressure plates. The 5 slideable means here shown for disconnecting outlet 17 with the housing comprises two telescoping tubes 18, 19, the inner tube 18 being adapted to be adjusted in the outer tube 19 by means of a screw bolt 21 connected to tube 18 and extending through an outer conduit 20 mounted in the housing. 10 The inlet 4 is shown connected with the housing by means of a tube 22 which is connected to and extends from the pressure plate 8 through a stuffing box 23 on the housing. The inlet 11 and outlet 16 are shown connected with ports in the housing by means of pipes 11^a and 16^a respectively. 15

In order to prevent the pressure plates, which have been heated by the entering driving medium, from being cooled to any 20 essential degree by the cold escaping driving medium I surround said plates with any suitable heat insulating medium as indicated by the numeral 24.

As before mentioned the pressure disks 25 may be connected by stay-bolts. This connection may also be carried out in other ways, for instance by means of a perforated drum or some other device which permits the escaping of driving medium. If stays be 30 used, they may be placed close to the rotating turbine disk and be vane shaped in cross-section, thereby giving the escaping driving medium such direction at different places of the periphery, that the least possible resistance is offered against it being conducted to 35 the outlet. The form of the screw-bolts shown is believed to be the most practical as an adjustment of the mutual distance of the pressure plates during the running of the turbine is easily effected by means of the nuts of the stays 9 being turned by means of a key 25 which extends through a stuffing box in the turbine house. Another means for effecting such an adjustment comprises, as indicated in Fig. 2, a concentric ring 26, arranged in the turbine house, and gearing by means of cogs or coupling arms with all the stay nuts 27, said nuts being thus turned simultaneously when the ring is turned. This 45 may be attained by means of a tangentially arranged screw 28 catching into corresponding teeth on ring 26 and passing out through the turbine house. The nut and screw devices thus arranged on the stay bolts may 50 also be replaced by a wedge device, wherein the wedges can be operated upon from the outside of the turbine house. The characteristic feature of these different adjusting devices consists therein that they are all 55 connected with and may be influenced by one or more parts which pass through the turbine house and are accessible from the outside of same.

Simpler forms of turbines are shown in 60 Figs. 3 and 4 wherein the housings 7^a and 7^b

respectively are provided with sides 34, 34^a respectively. In Fig. 3 the balancing pressure is received by a stationary plate 35 which is connected to the side cover 34 by means of stay bolts 37 while in Fig. 4 said 70 pressure is received by a stationary plate 36 connected to the turbine housing by means of bolts 37^a. In both figures the rotating disk 38 is provided with vanes on one side only. In Fig. 5 I have shown a single disk 75 29 having vanes mounted on both sides; the axial pressure of the driving medium being balanced by stationary vane systems mounted on pressure plates 30 and 31 situated on both sides of the disk inside the turbine housing and connected to each other by means of stay bolts 32. The driving medium is conducted to the vanes through an inlet channel 33.

As shown in Fig. 6, the wall of the turbine 80 housing next to the pressure plate 39 may be omitted by forming a suitable connection between said plate and the housing. This may be done by increasing the width of the periphery of the pressure plate to allow for 90 its movement on the housing and by interposing a suitable packing ring as 40 between a portion of said periphery and the housing.

Types of elastic fluid turbines may without any great amount of alteration be adapted 95 to dynamic compressors and the present invention may with advantage be also applied to radial compressors.

I claim:

1. In a turbine, a casing, a rotatable member 100 mounted therein, and a pressure plate mounted opposite the rotatable member, said pressure plate being connected with a fixed part by means of members located beyond the periphery of said rotatable member. 105

2. In a turbine, a casing, a rotatable member mounted therein, and a pressure plate mounted opposite the rotatable member, said pressure plate being connected with the turbine casing by means of members located 110 beyond the periphery of said rotatable member.

3. In a turbine, a turbine casing, a rotatable member therein, an adjustable member mounted opposite the rotatable member, and means within the casing beyond the periphery of the rotatable member to actuate the adjustable member. 115

4. In a turbine, a turbine casing, a rotatable member mounted therein, an adjustable pressure plate mounted opposite the latter and axially connected with the casing, and adjusting devices for the pressure plate beyond the periphery of the rotatable member. 120

5. In a turbine, a turbine casing, a rotatable member therein, a pressure plate opposite the latter, and stays beyond the periphery of the rotatable member connecting the casing and pressure plate. 125

6. In a turbine, a turbine casing, a rota- 130

table member therein, a pressure plate opposite the latter and adjustable stays beyond the periphery of the rotatable member connecting the casing and pressure plate.

5 7. In a turbine, a turbine casing, a rotatable member therein, a pressure plate opposite the latter, adjusting stays within the casing beyond the periphery of the rotatable member connecting the pressure plate and casing, and means outside the casing to actuate the stays.

15 8. In a turbine, a turbine casing, a rotatable member therein, a pressure plate opposite the latter, adjusting stays within the casing beyond the periphery of the rotatable member connecting the pressure plate and casing and means journaled in the casing to actuate the stays.

20 9. In a turbine, a turbine casing, a rotatable member therein, a normally stationary member movably mounted in the wall of the casing opposite the rotatable member, and

stay-rods within the casing beyond the periphery of the rotatable member connecting the stationary member with the casing. 25

10. In a turbine, a turbine casing, a normally stationary member having a central support projecting into the casing, a packing surrounding the support, a shaft extending through the stationary member, a rotatable 30 member fixed on the shaft, stay-rods connected with the stationary member within the casing beyond the periphery of the rotatable member adapted to adjust said stationary member, and means outside the casing 35 to actuate the stay-rods.

In testimony, that I claim the foregoing as my invention, I have signed my name in presence of two subscribing witnesses.

BIRGER LJUNGSTRÖM.
